CLAIM

I claim the ornamental design for a modular flat deck, skirting, and canopy for a vehicle, truck, or the like, as shown and described.

DESCRIPTION

FIG. 1 is a perspective rear left side view of a modular flat deck and skirting for a vehicle, truck, or the like showing my new design;

FIG. 2 is a perspective rear right side view thereof;

FIG. 3 is a left side elevation view thereof;

FIG. 4 is a right side elevation view thereof;

FIG. 5 is a front elevation view thereof;

FIG. 6 is a rear elevation view thereof; and,

FIG. 7 is a top plan view thereof.

1 Claim, 3 Drawing Sheets
